APRON OR SIMILAR ARTICLE

Daniel B. Schwartzman, Englewood, N. J.

Application November 4, 1950, Serial No. 12,845

Term of patent 7 years

(Cl. D3—26)

To all whom it may concern:

Be it known that I, Daniel B. Schwartzman, a citizen of the United States, residing at Englewood, in the county of Bergen and State of New Jersey, have invented a new, original, and ornamental Design for an Apron or Similar Article, of which the following is a specification, reference being had to the accompanying drawing, forming part thereof.

In the drawing:

Fig. 1 is a front perspective view of an apron or similar article showing my new design;

Fig. 2 is a rear perspective view thereof; and

Fig. 3 is a partial front perspective view with a pair of strap flaps lifted to expose a pair of pocket openings.

I claim:

The ornamental design for an apron or similar article as shown and described.

DANIEL B. SCHWARTZMAN.
